UNITED STATES PATENT OFFICE.

ROBERT GAUCK, OF BANT, GERMANY.

PENHOLDER PROVIDED WITH DEVICE FOR DRYING PENS.

SPECIFICATION forming part of Letters Patent No. 658,772, dated October 2, 1900.

Application filed January 9, 1900. Serial No. 858. (No model.)

To all whom it may concern:

Be it known that I, ROBERT GAUCK, a subject of the King of Prussia, Emperor of Germany, residing at Bant, near Wilhelmshaven, 5 in the Kingdom of Prussia and German Empire, have invented certain new and useful Improvements in Penholders Provided with a Device for Drying the Pen, (for which I have applied for patents in England, No. 24,021, 10 dated December 2, 1899; in Germany, dated November 25, 1899; in France, dated December 2, 1899; in Austria, dated November 27, 1899; in Hungary, dated November 30, 1899; in Switzerland, dated November 27, 1899, and 15 in Belgium, dated December 2, 1899,) of which the following is a specification.

The object of this invention is to provide a penholder with a drying device by means of which the pen can be dried after use. A pen 20 dried in this manner lasts much longer than usual.

In order that my said invention may be properly understood, I have hereunto appended an explanatory sheet of drawings, 25 which shows, by way of example, one form of the device.

On the drawings, Figure 1 is a longitudinal section of a penholder, showing the drying device in operation, while Fig. 2 is a similar section showing the drying device in the 30 position it occupies when the pen is being used for writing purposes.

As will be seen from the drawings, the device consists of a spring-lever arrangement 35 having attached to it two absorbent-pads which absorb the ink when they come in contact with the pen.

The device shown consists, essentially, of two bell-crank levers *a b*, which are pivoted 40 to the penholder *c* by means of the pins *c'* in such a manner that they can be partially rotated about said pins. These bell-crank levers *a b* are jointed at *d'* to the upper ends of the slide-rods *d*, whose other ends are connected together by means of the pin *e*, which latter also passes through the end of the guide-spindle *g*. The pin *e* moves up and down in a slot in the penholder, and its two ends are attached to a ring *f*, which can also move 45 freely on the outside of the penholder. A spiral spring *h* is coiled around the guide-

spindle *g* and tends to constantly press the slide-rods *d* upward.

The mode of operation is as follows: In Fig. 2 the bell-crank levers *a b* are shown in a position 55 of rest, and they are held in this position by means of the spring *h*, which presses on the slide-rods *d*. When the ring *f* is moved in the direction of the arrow *x*, the slide-rods *d* will also move and rotate the bell-crank levers *a b* 60 on their pins *c'*, causing them to move outward from the penholder in the direction of the dotted lines to the extent of about forty-five degrees. Thereafter a further slight pressure outward by the fingers will cause the 65 bell-crank levers to pass their dead-points, and, as shown in Fig. 1, the spring *h* will then move the ring *f* in the direction of the arrow *y* and at the same time cause the slide-rods *d* and bell-crank levers *a b* to assume the position shown 70 in full lines at Fig. 1—that is, the position in which the absorbing-pads *l* are pressed against the sides of the pen *i*.

When it is desired to bring the device back into the closed position, Fig. 2, the ring *f* is 75 moved in a direction opposite to the arrow *y*, Fig. 1, with the result that the bell-crank levers are caused to move in the direction of the arrows *z*, Fig. 1. A slight pressure inward by the fingers causes the bell-crank levers to pass 80 their dead-points, whereupon the pressure exerted by the spring *h* on the slide-rods *d* brings the device back into the closed position.

What I claim, and desire to secure by Letters Patent of the United States, is—

1. The combination with a penholder, of a pen-wiper consisting of a pair of levers each provided with a wiping-pad and means for throwing the levers into and out of operative 90 position with respect to the pen, substantially as described.

2. The combination with a penholder of a pen-wiping device consisting of a pair of levers carrying pads, said levers being pivoted 95 to the penholder and a single device to which both of said levers are connected whereby they may be simultaneously thrown into and out of operative position.

3. The combination with a penholder of a 100 pair of bell-crank levers carrying pads, a thrust-rod connected with both levers and a

spring acting against said thrust-rod, whereby the levers will be held either in their operative or inoperative position.

4. The combination with a penholder of a pen-wiping device consisting of a pair of levers carrying pads, a spring acting upon both levers and tending to hold them either in operative position with respect to the pen, or

out of such operative position, substantially as described.

In testimony whereof I have hereunto set my hand in the presence of two witnesses.

ROBERT GAUCK.
